JULIUS R. WELK, OF CHURCHBRIDGE, SASKATCHEWAN, CANADA

PUMP

Application filed April 8, 1930, Serial No. 442,600, and in Canada December 12, 1929.

The invention relates to improvements in pumps and particularly to well pumps and an object of the invention is to provide a construction which will permit of the easy and quick repairing or replacing the plunger leathers when such is required and without necessitating the removal of the pump and associated parts from the well.

A further object is to construct the pump in a simple, durable and inexpensive manner and so that the replacements or repairs can be made with little trouble and without requiring many or special tools for carrying out the work.

With the above more important objects in view, the invention consists essentially in the arrangement and construction of parts hereinafter more particularly described, reference being had to the accompanying drawings, in which:—

Fig. 1 is a side view of the pump.

Fig. 2 is an enlarged detailed vertical sectional view centrally through the same, parts being broken away and certain parts being shown in side elevation.

Fig. 3 is a horizontal sectional view at 3—3

Figure 2.

Fig. 4 is a horizontal sectional view at 4—4

Figure 2.

Fig. 5 is a perspective view of the upper, cylinder cap.

Fig. 6 is a perspective view of the bottom cylinder collar.

Fig. 7 is an enlarged detailed vertical sectional view through the plunger.

Fig. 8 is a horizontal sectional view at 8—8

Figure 7.

In the drawings like characters of reference indicate corresponding parts in the several figures.

Considerable difficulty is at present experienced with pumps now on the market due to the structural arrangement of the same being such that when repairs are necessary, such as the replacement of the plunger leathers, the entire pump or a considerable part thereof has to be removed from the well.

According to my invention, however, and where it is possible for one to descend into the well, it is not necessary to disturb the

pump as the construction provided is such that one by descending into the well and due to the construction provided, can obtain easy access to the plunger and insert new plunger leathers and replace the parts.

The pump cylinder 1 is of predetermined length and diameter depending on the capacity and stroke required. The upper end of the cylinder is received within a collar 2 being butted against a gasket 3 engaging an internal ledge formed on the collar. The lower end of the cylinder is received within a collar 4, the lower end of the collar being internally screw threaded to receive a nipple 5 and being provided above the nipple with an inserted valve seat 6. A weighted valve 7 of well known type is located at the lower end of the cylinder being jammed between the cylinder and the lower collar, such valve being designed to open upwardly on the suction stroke of the plunger later described and to close downwardly against the seat 6.

A closure cap 8 is applied on the upper end of the collar 2, a gasket 9 being inserted and the cap and the collars are provided with side lugs 10 which are provided with holes 11 to receive similar tie rods or bolts 12 which have screw threaded ends. The lower ends of the bolts are provided above and below the lugs of the lower collar with nuts 13 and 14 which when tightened up permanently fasten the tie rods to said latter collar. The upper ends of the bolts are provided with nuts 15 which when screwed down permanently fasten the cap in place and the several parts together as will be readily understood.

The collar 2 is provided with a side opening 2' and is flanged and faced as shown so that it can be fastened by bolts 16' to the flanged and faced side of a vertically disposed sleeve 16 which has the ends thereof screw threaded. A gasket 17 is placed between the flanges to insure of a water tight joint. It will be observed that the sleeve is provided with an internal partition 18 above which is an L-shaped passage or duct 19 communicating with the opening 2'.

A sleeve 20 is screw threaded to the lower end of the nipple 5 and the sleeve is pro-

vided with a laterally extending upturned elbow 21, the elbow receiving the screw threaded lower end of a supporting pipe 22, the upper end of which is screwed into the 5 lower end of the sleeve 16. A plug 23 is inserted at the lower end of the pipe 22 to prevent water from passing upwardly through such pipe as said pipe is simply used as a reinforcement for the sleeve 16. A water pipe 10 24 is screw threaded into the lower end of the sleeve 20 and extends downwardly into the well as is usual. A water pipe 25 is screw threaded into the upper end of the sleeve 16 and the upper end of the water pipe screw 15 threads into a downturned elbow 26' formed integrally with a top sleeve 26, the latter sleeve being aligned with the central vertical axis of the cylinder which it overlies.

A water delivery pipe 27 extends upwardly from the sleeve 26 to the top of the well and I have herein shown a bushing 28 as screw threading into the sleeve 26 and screw threaded to receive the pipe 27. A comparatively short upper cylinder 29 is screw threaded 20 into the lower end of the sleeve 26 and this cylinder slidably receives an upper plunger 30 carried by the upper end of an outlet pipe 31, the lower end of which screw threads centrally into the cap 8.

30 The plunger 30 is shown as formed from a leather fastened between two nuts applied on the upper screw threaded end of the pipe 31.

Within the cylinder 1, I locate slidably the 35 lower or main pump plunger 32, the details of which will be later described and this plunger is detachably connected to the lower end of the plunger rod 33 which passes freely upwardly through the cap, the pipe 31, the sleeve 26 and the pipe 27 to the top of the well at which point means not herein shown is provided for reciprocating the rod in the usual manner. It will be particularly observed that the pipe 31 just nicely clears the 40 pump rod and that such pipe is considerably smaller than the cylinder 29 and that the cap 8 to which the pipe 31 is connected can be easily and quickly removed from the sleeve 2 by undoing the nuts 15. The reason for this 45 will be elaborated upon later.

The main plunger 32 embodies an interior sleeve 34 having an inturned flange 35 at the upper end thereof forming a valve seat and an inverted L-shaped flange 36 at the 55 lower end thereof. An upper and an intermediate ring 37 and 38 are placed on the sleeve and the customary plunger leathers 39 and 40 envelope the rings and are caught respectively, the upper one between the rings 60 and the lower one between the intermediate ring and the flange 36. The upper ring is provided with a three armed bridge 41 within which is located a gravity valve 42 engageable with the seat formed by the flange 65 35, the valve being provided with a centre tit

43 as is usual. The plunger parts are fastened together by three similar bolts 44 passing downwardly through the arms of the bridge, the said bolts having their heads 45 engaging the flange 36 and their upper ends screw threaded to receive nuts 46 engaging the upper edges of the arms of the bridge as best shown in Figure 7.

Centrally to the bridge, I secure a short rod 47 which has the upper end screw threaded and entering a coupling sleeve 48, the coupling sleeve being screw threaded on the end of the pump rod 33.

The above construction of the plunger permits the plunger to be taken apart by undoing the nuts and removing the bolts and obviously when this is done, the rings can be lifted to permit of the removal of worn leathers and the insertion of new leathers. This being accomplished, the bolts can be re-inserted and the nuts applied and tightened up.

In order that the advantages of my pump construction may be fully understood, I will now describe the manner in which one will replace the worn leathers of the plunger. The well will be entered and descended until one is within convenient working range of the upper end of the cylinder 1, it being understood that a wrench and a new set of leathers are carried on the person. Having arrived at the main cylinder, the nuts 15 are undone. This releases the cap 8 which is then lifted to clear it from the collar and the projecting end of the bolts and in this connection, it will be noted that the upper plunger 30 is free to slide upwardly in the upper cylinder which latter in actual practice will probably be eight inches long and say two inches in diameter. This gives access to the plunger rod and here I might explain that prior to descending the well, the pump handle or the like will be pressed down to bring the plunger 32 to the upper end of its stroke which is in a location below the outlet 2'. Accordingly, when the cap is raised as above explained, the coupling sleeve 48 appears, such sleeve protruding above the upper level of the collar 2, it being here observed that the cap 8 is arched in vertical cross section.

The operator then uses his wrench to unscrew the coupling sleeve from the lower end of the pump rod and here it will be noted that, as the pump rod has not been disconnected from the pump handle or the like at its upper end, the said rod is anchored and as the main plunger can rotate in the main cylinder, the coupling sleeve can be readily disconnected. Having disconnected the coupling sleeve, one then swings the raised cap 8 laterally and this can be readily done as the upper plunger is free to swing in the upper cylinder and ample clearance space is reserved between the pipe 31 and the cylinder 136

29. While holding the cap and contained plunger rod in its latter position, one grabs the short rod 47 and lifts the main plunger from the cylinder 1. The nuts 46 can then 5 be undone and the new leathers substituted for the worn ones.

This being accomplished, the repaired plunger 32 is inserted again in the cylinder 1 and shoved down. The cap 8 is swung 10 back to a position above the collar 2 being retained in an elevated position until the short length of rod 47 has been screwed back into the coupling sleeve 48. Finally the cap 8 is dropped down to its initial position and 15 receives the upper ends of the bolts 12 and the nuts 15 are re-applied and tightened up.

It will be particularly noted that the upper plunger in contact with its cylinder prevents any leakage of water when the pump 20 is in use and such arrangement permits of the necessary free up and lateral movement required to position the cap 8 so that the disconnected main plunger can be freely raised out of the main cylinder and further it will 25 be seen that the construction provided permits of the easy and quick replacement of worn leathers without having to remove the pump from the well or disconnect any of the pump parts other than the cap 8 and the main 30 plunger so that the complete work can be done by a single operator.

The pump operates in the ordinary manner, water rising in the lower end of the cylinder 1 on the up stroke of the plunger 32, 35 the valve in the lower end of said cylinder opening on such stroke. On the down stroke of said plunger, the plunger valve 42 opens and the water entering above the plunger is discharged upwardly through the pipe 27 40 in the subsequent up stroke of the plunger, such water passing to the pipe 27 through both of the pipes 31 and 25, the greater portion going through the pipe 25 due to its larger cross sectional area.

45 While I have given a detailed description of the various collars, sleeves and elbows utilized, it will be readily understood that these can be modified without departing from the spirit of the invention.

50 If the valve 7 should at any time need to be replaced, this can be accomplished by undoing the bolts 16 which permits the main cylinder and parts associated therewith to be raised, the lower end of the cylinder lifting out of the collar 4 and exposing the valve 7, it being of course understood that the nuts 15 are undone.

What I claim as my invention is:—

1. The combination with a pump cylinder, a pump plunger operating therein and a removable cap closing the upper end of the cylinder, of a water discharge pipe axially aligned with the cylinder and having the lower end thereof terminating at some distance above the cylinder cap, an upstanding

water outlet pipe having the lower end thereof permanently secured to the cap and opening to the interior of the cylinder, an upper cylinder communicating with the water discharge pipe and freely receiving the water outlet pipe, a packed pipe head mounted on the upper end of the water outlet pipe and slidably received in the upper cylinder and a pump rod extending downwardly through the water discharge and outlet pipes and cap and detachably connected adjacent its lower end to the pump plunger. 70

2. The combination with a pump cylinder, a pump plunger operating therein and a detachable cap closing the upper end of the cylinder, of an upwardly extending water discharge pipe axially aligned with the cylinder and having its upper end terminating at some distance above the cylinder cap, a laterally positioned upstanding branch pipe having the upper end communicating with the discharge pipe and the lower end communicating with the upper end of the cylinder, a vertically disposed outlet pipe having the lower end thereof secured centrally to the cap, means maintaining a water tight connection between the upper end of the latter pipe and the discharge pipe, said means being located below the adjacent upper end of the branch pipe and permitting upon the detachment of the cap of the end shifting of the outlet pipe and of a limited lateral movement of the lower end thereof and a plunger rod passing downwardly through the discharge and outlet pipes and through the cap and detachably connected to the plunger adjoining the same. 80

3. The combination with a pump cylinder and main plunger slidably operating therein, of a collar receiving the upper end of the plunger and provided with a lateral water outlet a cap detachably secured to the upper end of the collar, a vertically extending water discharge pipe axially aligned with the cylinder and having the lower end thereof terminating at some distance from the cylinder cap, a sleeve mounted on the lower end of the pipe and provided with a lateral inlet, a laterally positioned branch pipe connecting the lateral outlet and inlet, an outlet pipe having the lower end secured centrally to the cap and opening to the interior of the cylinder, an upper cylinder extending downwardly from the lower end of the sleeve and freely receiving the upper end of the outlet pipe, a packed pipe head secured to the upper end of the outlet pipe and slidably operating in the upper cylinder and a pump rod extending downwardly through the discharge pipe, the sleeve, outlet pipe and cap and detachably fastened to the main plunger adjacent the same. 90

4. A pump having a detachable closure cap for the cylinder thereof, an outlet pipe secured to the cap and connected by a water 100

105

110

115

120

125

130

tight connection to an overlying water discharge pipe, the connection permitting, upon detachment of the cap, of the raising of the outlet pipe and of a limited lateral movement thereof and a pump rod passing downwardly through the outlet pipe and detachably connected to the pump plunger adjacent the same.

5. In a pump, the combination with a cylinder, plunger therein and a water discharge pipe axially aligned with the cylinder and terminating at some distance above the same, of an upper cylinder communicating with the lower end of the discharge pipe, a packed pipe head slidably mounted in the latter cylinder, an outlet pipe extending downwardly from the head and freely received in the upper cylinder, a cap secured to the lower end of the latter pipe and detachably fastened to the pump cylinder and a pump rod extending downwardly through the pipes and detachably connected to the pump plunger adjacent the same.

6. In a pump, the combination with a cylinder, plunger therein and a water discharge pipe axially aligned with the cylinder and terminating at some distance above the same, of an upper cylinder communicating with the lower end of the discharge pipe, a packed pipe head slidably mounted in the latter cylinder, an outlet pipe extending downwardly from the head and freely received in the upper cylinder, a cap secured to the lower end of the latter pipe and detachably fastened to the pump cylinder, a pump rod extending downwardly through the pipes and detachably connected to the pump plunger adjacent the same and a branch pipe connecting the upper end of the cylinder with the discharge pipe, said branch pipe communicating with the discharge pipe in a location above the upper cylinder.

Signed at Winnipeg, this 2nd day of October, 1929.
